VALVE LIFTER

Stanton Palmer, Chicago, Ill., assignor, by mesne assignments, to Snap-on Tools, Inc., Kenosha, Wis., a Corporation of Delaware

Application March 29, 1930. Serial No. 439,866

4 Claims. (Cl. 29—86.3)

This invention relates to valve lifters and more particularly to collapsible valve lifters, although certain features thereof may be employed with equal advantage for other purposes.

- 5 It contemplates more especially the provision of complementary elements capable of ready association and dismantling to provide a valve lifter of variable frame structure for selective collapse during the non-use thereof.
- 10 Valve lifters are usually bulky and lack the necessary compactness to enable their placement in tool kits or other storage space so as to occupy a minimum area during the non-use or transportation thereof. This is an important factor both in the requirement of less expensive containers and minimizing transportation cost to the extent that the vendor may conveniently maintain a supply thereof on a shelf without occupying an appreciable space. Moreover,
- 15 20 the mechanic finds it necessary to keep such equipment under lock and key, and the ordinary valve lifter assembly does not afford such protection owing to the bulk thereof. As a consequence, a collapsible valve lifter which does not require complete dismantling, is an important asset to manufacturer, vendor and the user in that such affords simple and inexpensive manipulation from the standpoint of production, sales and use.
- 25 30 One object of the present invention is to simplify the construction and improve the operation of devices of the character mentioned.

Another object is to provide valve lifter structure which is collapsible without requiring complete dismantling of the component elements thereof.

Still another object is the provision of a valve lifter frame having a yoke and jaws pivotally associated therewith for selective collapse without dismantling.

A further object is to provide a frame having a pivotally associated yoke and jaws capable of adjustment to a rigid confronting position.

A still further object is to provide a frame having jaws and a yoke associated therewith for collapse with a removable actuator therefor.

Still a further object is to provide novel means for collapsibly associating yoke and jaw members with a frame to enable the ready assembly thereof in rigid operative relations.

Other objects and advantages will appear from the following description of an illustrative embodiment of the present invention.

55 In the drawing:

Figure 1 is a side view in elevation of a device embodying features of the present invention, parts thereof being in section to clarify the showing.

Figure 2 is a view of the device shown in Figure 1 in its collapsed position to illustrate the compactness thereof for shipment, storage and protected placement by the user during the non-use thereof.

Figure 3 is a plan view of one form of jaws capable of use with a frame of the type herein disclosed.

Figure 4 is a perspective view of the jaws shown in Figure 3.

Figure 5 is a perspective view of a modified jaw constituting an extension of the frame work disclosed in Figure 1.

Figure 6 is a view of a modified frame capable of use in conjunction with valve lifter jaws and actuator means.

Figure 7 is a perspective view of a wing nut employed in connection with a device for assembly of the component elements thereof.

The structure selected for illustration comprises a frame 10 stamped or otherwise shaped from a metallic bar or other sheet material to define confronting arms 11 and 12 which, in this instance, present a U-shaped contour thereto. As shown, the frame 10 is manipulated so that the arms 11 and 12 thereof are disposed horizontally to receive a yoke 13 and valve lifter jaws 14, respectively, of any desired construction as commercial practice may dictate.

The yoke 13 comprises, in this instance, a tubular housing 15 which is bifurcated to present confronting resiliently related arms 16 spaced to receive the frame arm 11 therebetween for pivotal connection therewith. The pivotal connection is afforded, in this instance, by threaded fastener 17 which extends through aligned apertures therein for reception of a threaded nut 18 thereon to maintain the elements in assembled relation. So that the yoke 13 may be maintained in alignment with the arm 11 in its operative position, another threaded fastener 19 extends through the confronting arms 16 thereof for reception in a notch 20 proximate to the extremity of the arm 11 for communication with the lower edge 21 thereof. In consequence thereof, the yoke 13 may be pivoted in a counter-clockwise direction (viewed from Figure 2) so that the fastener 19 will engage the notch 20 whereupon a wing nut 22 in threaded engagement therewith may be tightened to effect the frictional engagement of the yoke arms 16 with the frame arm 11.

thereby holding the tubular housing 15 with its bore 23 with its axis vertical.

In order to support the spring surrounding the stem of the valve, the jaws 24 are detachably associated with the arm 12 of the frame 10 for axial alignment with the bore 23 of the yoke housing 15. To this end, the jaws 24 comprise confronting complementary elements having arms 25 and 26 which terminate in extensions 27 and 28 preferably though not essentially provided with circularly arcuate jaws 29 for termination in outwardly curved prongs 30. The prongs 30 are spaced for resilient spreading to conform with the exterior contour of the spring which is received between the arcuate portions 29 for support upon transversely extending flanges 31, in this instance stamped therefrom for confronting approach in the same plane, the flanges 31 serving to sustain the valve spring for compression by the valve displaced in a descending direction by an actuator to be hereinafter described.

As shown, the jaws 24 have the arms 25 and 26 thereof provided with spaced aligned apertures 32 and 33 which are adapted to receive threaded studs 34 therethrough for connection to similarly apertured confronting extensions 35, these being retained or fixedly mounted thereto by means of wing nuts 36 which enable the ready detachment thereof. Extensions 35 and 36 constitute elongated bars which are provided with the necessary convergents for reception between the jaw arms 25 and 26, they being of the necessary length so that the arcuate jaws 29 will be in axial alignment with the bore 23 of the housing 15. To this end, the extensions 35 are provided with apertures spaced for alignment with corresponding apertures provided in the arm 12 of the frame 10 for the reception of a threaded stud 36 therethrough which has a nut 37 in threaded engagement therewith to retain the extensions 35 with the jaws 29 thereof in pivotal association with the frame 10.

Another threaded stud 38 projects through the aligned apertures in the extensions 35 for the reception of a wing nut 39 thereon, which extends transversely therebetween for engagement of a notch 40 provided in the arm 12 proximate to the extremity thereof in communication with its upper edge 41, thereby limiting the clockwise pivotal movement of the jaws 29 for alignment with the arm 12. In this position the wing nut 39 is tightened so as to preclude any displacement between the jaws 29 and the arm 12, thereby establishing a rigid assembly for cooperation with an actuator to be presently described.

The actuator comprises, in this instance, a cylindrical housing 42 which is shaped for telescopic association with the bore 23 of the yoke housing 15 which is in frictional engagement therewith owing to a threaded stud 43 which projects through an aperture 44 on the arms 16 thereof in the region of the housing 15 for threaded engagement with the other arm 16 to effect the approach or spreading thereof depending upon the directional rotation of the threaded stud 43. The threaded stud 43 has an enlarged head 45 for the reception of a rod 46 transversely therethrough to enable the tightening or loosening of the stud 43 to hold or enable axial displacement of the cylindrical housing 42 in the bore 23 within the limits of its length. This affords the adjustment of the cylindrical housing 42 with respect to the jaws 29 so that a plunger 45' may be actuated to compress the valve spring within the limits of its movement.

The plunger 45' is axially slidable within the housing 42, it being guided by a bushing 46' which has a threaded periphery 47 for adjustable engagement with the corresponding interiorly threaded mouth of the plunger housing 42. As shown, the bushing 46' terminates in upwardly extending furcations 48 adapted to receive a pivot pin 49 therebetween to sustain a cam 50 eccentrically mounted thereon. The cam 50 terminates in a lever 51 which affords the necessary manual rotation thereof to downwardly displace the plunger 45' having the extremity thereof in frictional peripheral engagement with the cam 50. A coil spring 52 envelops the plunger 45' within the housing 42 for engagement with a collar 53 fixed thereto by means of a pin 54, the other extremity of the coil spring 52 bearing against a shoulder 55 provided by the housing 42 to normally urge the plunger 45' in an upward direction so that its extremity will be in engagement with the periphery of the cam 50 in all positions thereof.

A lug 56 projects from the cam 50 at its juncture with the lever 51 to limit the clockwise rotation thereof (viewed from Figure 1) in effecting the descent of the plunger 45' which engages the head of the valve to effect the descent thereof to compress the spring which is supported on the flanges 31 of the jaws 29, thereby enabling the removal of the pin and its associated parts for valve grinding or replacements as conditions may require. With this arrangement, the plunger 45' may be roughly adjusted to confront the valve spring jaws 29 for any particular engine construction by manipulating the pin 46 which enables the turning adjustment of the stud 43 extending between the bifurcated tubular housing 15 to increase or decrease the extent of the bore 23 so that the plunger housing 42 will be adjustable therein or held against displacement, respectively. Thereupon, the lever 51 is manipulated for pivotal movement about its fulcrum 41 to depress the plunger 45 to accomplish the intended purpose.

Different engine constructions require special frames to provide the necessary accessibility to the valves. This knock-down construction enables the frame 10 to be substituted with similar bars of different configuration to meet any particular commercial requirement. In the present embodiment, a frame 10' comprising an inclined bar with respect to its arms 11' and 12', is capable of association with the yoke 15 and jaws 29 in the usual manner as described supra in connection with the embodiment disclosed in Figure 1. In this instance, however, the extension 35 is dispensed with, and the jaw shanks 25 and 26 directly applied for assembly with the arm 12'. The inclination of the frame 10' is such as to bring the jaws 29 in axial alignment with the plunger 45 held by the yoke 13, thereby enabling the ready substitution of different shaped frames 10 for use in connection with different engine constructions.

Various changes may be made in the embodiment of the invention herein specifically described without departing from or sacrificing any of the advantages of the invention as defined in the appended claims.

I claim:

1. In a collapsible valve lifter, the combination with a frame, of a yoke pivotally associated with said frame, valve spring receiving jaws pivotally associated with said frame for confronting assembly with said yoke, actuator means associated

with said yoke, fastener means on said yoke to enable the axial adjustment of said actuator means therein, and fastener means for maintaining said pivotal yoke and jaws in rigid spaced operative relation.

5 2. In a collapsible valve lifter, the combination with a frame, of a yoke pivotally associated with said frame, valve spring receiving jaws detachably associated with said frame for confronting assembly with said yoke, actuator means associated with said yoke, fastener means on said yoke to enable the axial adjustment of said actuator means therein, frame connecting means for said yoke and jaws to enable the pivotal collapse thereof relative to said frame, and adjustable fastener means for maintaining said yoke and jaws in operative position against collapse.

10 3. In a collapsible valve lifter, the combination with a frame, of a yoke pivotally associated with said frame, valve spring receiving jaws detachably associated with said frame for confronting assembly with said yoke, actuator means associated with said yoke, and adjustable fasteners for said yoke and jaws to enable the pivotal collapse thereof relative to said frame, said adjust-

15 25

able fasteners comprising screw means on said frame serving as a pivot for said yoke and jaws, there being notches in said frame, and other screw means on said yoke and jaws spaced from said pivotal screw for cooperation with said notch to hold said yoke and jaws in confronting assembled relation.

16 4. In a collapsible valve lifter, the combination with a frame, of a yoke pivotally associated with said frame, valve spring receiving jaws detachably associated with said frame for confronting assembly with said yoke, actuator means associated with said yoke, and adjustable fasteners for said yoke and jaws to enable the pivotal collapse thereof relative to said frame, said adjustable fasteners comprising screw means on said frame serving as a pivot for said yoke and jaws, there being notches in said frame, other screw means on said yoke and jaws spaced from said pivotal screw for cooperation with said notch to hold said yoke and jaws in confronting assembled relation, and fastener means on said yoke to maintain said actuator means in adjusted position.
